CLAIM

The ornamental design for a wallet, as shown and described.

DESCRIPTION

FIG. 1 is a front, perspective view of a wallet of my design.

FIG. 2 is a rear, perspective view of the wallet of FIG. 1.

FIG. 3 is a bottom view of the wallet of FIG. 1.

FIG. 4 is a top view of the wallet of FIG. 1.

FIG. 5 is a first side view of the wallet of FIG. 1.

FIG. 6 is a second side view of the wallet of FIG. 1.

FIG. 7 is a front view of the wallet of FIG. 1; and,

FIG. 8 is a rear view of the wallet of FIG. 1.

The dash-dash-dash-dash type broken lines shown in the drawings are included for the purposes of illustrating portions of the wallet and form no part of the claimed design. Randomly dashed lines represent surface shading.

The dot-dash-dot-dash type broken lines shown in the drawings define the boundaries of the claimed design.
